UNITED STATES PATENT OFFICE.

ALBERT G. NELSON, OF EAST PORT CHESTER, CONNECTICUT.

FLASHING.

Application filed December 21, 1921. Serial No. 523,855.

To all whom it may concern:

Be it known that I, ALBERT G. NELSON, a citizen of the United States, residing at East Port Chester, in the county of Fairfield and 5 State of Connecticut, have invented certain new and useful Improvements in Flashings, of which the following is a full, clear, and exact specification.

This invention relates to flashings for use 10 around chimneys or on parapet walls, and has for its object to provide an improved and simplified construction of flashing which may be quickly positioned and will effectively prevent leaks around the chimneys or 15 walls to which it may be attached.

A special object is to construct the flashing in such a way that expansion and contraction of the metallic members thereof under varying climatic conditions will be 20 automatically compensated for, whereby the tendency of prior constructions of flashings to pull away or separate from the chimneys or walls under such conditions is avoided.

Another important object is to provide 25 simplified means for supporting the flashing on the chimney or wall, said supporting means being readily attachable after the chimney or wall has been erected and without weakening the same. Other objects will 30 appear as the description proceeds.

The invention will be first hereinafter described in connection with the accompanying drawings, which constitute part of this specification, and then more specifically defined in the claims at the end of the description. 35

In the accompanying drawings, wherein similar reference characters are used to designate corresponding parts throughout the 40 several views:—

Figure 1 is a perspective view of a chimney and adjacent portions of the roof showing a flashing constructed substantially in accordance with this invention applied 45 thereto, and

Figure 2 is a vertical section through the flashing drawn to a larger scale.

While the drawings show the flashing applied to a chimney 1, where it protrudes 50 from the roof 2, it will be understood that said flashing may also be used on parapet walls with equal success. Said flashing consists of two metallic members or strips 3 and 4, both of which are supported in proper 55 position on the chimney or wall 1 by L-shaped hooks or brackets 5 which may be

positioned in said wall when the latter is being erected or driven into the same after its completion.

The lower member 3 of the flashing has 60 its upper edge turned inwardly and downwardly to form a horizontally extending portion 6 adapted to rest upon the upper ends of the brackets 5, and a downwardly extending portion 7 arranged parallel to 65 and spaced from the vertical outer portion 8 of said member. The lower edge portion 9 of the member 3 is bent inwardly from the outer vertical portion 8 to contact with the roof 2 adjacent the chimney wall. The 70 lower extremity of said portion 9 is preferably bent upon itself, as at 10, providing a rounded edge 11 to contact with one or more layers of builders' paper 12 usually placed over the juncture of the roof and chimney 75 wall.

The upper member 4 of the flashing has 80 a horizontal portion 13 with a downwardly extending hook-shaped portion 14 at its inner edge to fit around the vertical portion 80 7 of the member 3 and rest upon the brackets 5. From the outer edge of the portion 13 an inclined portion 15 extends upwardly and toward the chimney wall, terminating 85 a short distance from the latter. The upper edge of said inclined portion 15 is preferably bent upon itself, as at 16, leaving a rounded edge 17 arranged near said wall. The lower edge of said inclined portion 15 extends below the horizontal portion 13, as 90 at 18, in order to deliver the drip from said inclined portion, which acts as a water shed, away from the chimney wall and the inter-engaging portions of the members 3 and 4 of the flashing. 95

The space between the chimney wall and the inclined portion 15 of the member 4 is filled with plastic material 19 down to the horizontal portion 13 and up to the rounded edge 17 of said inclined portion 15. When 100 said plastic material has set it forms a water tight seal between the member 4 and the chimney wall so that all moisture is prevented from running down the outer surface of said wall and entering the joint 105 of the roof therewith.

In positioning the flashing, the lower metallic member 3 is first hooked over the brackets 5, which have been previously fixed in the wall at proper intervals, and the metallic member 4 is then inserted endwise 110 so that its hook-shaped portion 14 will rest

upon said brackets and below the vertical inner portion 7 of the member 3. When thus assembled, the members 3 and 4 will be retained in position by the inwardly bent 5 lower portion 9 of said member 3, and the connection between said members will be such as to automatically compensate for expansion and contraction which may take place in either or both of said members 10 under varying climatic conditions. Because of the fact that the interengaging portions 7 and 14 of the members 3 and 4 do allow for such compensation, the tendency of the upper edge 17 of the inclined portion 15 to break away from the plastic filling 19, or to pull said plastic filling away from the chimney wall, is greatly reduced, so that under ordinary conditions the joints between said plastic filling, member 4 and 20 chimney wall, will remain intact. If a fissure should be formed between these parts as a result of unusual conditions, said fissure may be quickly filled and the leak stopped with plastic material similar to 25 that used for the original filling 19.

I claim:

1. In a flashing, the combination with 30 upper and lower metallic members having interengaging marginal portions, of brackets projecting from a wall for supporting the flashing thereon, said interengaging portions being arranged between said brackets and wall.

2. In a flashing, the combination with 35 upper and lower metallic members having interengaging marginal portions, of brackets projecting from a wall for supporting the flashing thereon, said interengaging portions being arranged between said brackets and wall, and the lower marginal portion of said lower member being turned inwardly toward the wall below said brackets for the purpose specified.

3. In a flashing, the combination with 45 upper and lower metallic members having interengaging marginal portions, of brackets projecting from a wall for supporting the flashing thereon, said interengaging portions being arranged between said brackets and wall, and said upper member having an inclined portion forming a water 50 shed and extending outwardly beyond said interengaging portions of the members.

4. In a flashing, the combination with 55 upper and lower metallic members having interengaging marginal portions, of brackets projecting from a wall for supporting the flashing thereon, said interengaging portions being arranged between said brackets and wall, said upper member having an 60 outwardly extending horizontal portion and an upwardly extending inclined portion projecting below the outer edge of said horizontal portion for the purpose specified.

5. In a flashing, the combination with 65 upper and lower metallic members having interengaging marginal portions, of brackets projecting from a wall for supporting the flashing thereon, said interengaging portions being arranged between said 70 brackets and wall, said upper member having outwardly and upwardly extending portions, the latter reaching near to the wall, and a filling of plastic material in the space between the wall and said outwardly 75 and upwardly extending portions.

6. In a flashing, the combination with 80 upper and lower metallic members, said lower member having its upper margin turned inwardly and downwardly and spaced therefrom, said upper member having its lower margin turned outwardly and upwardly to embrace said downwardly turned margin of the lower member, and brackets fixed in a wall and extending outwardly beyond said interengaging marginal 85 portions of said members for supporting the flashing on the wall.

7. In a flashing, the combination with 90 upper and lower metallic members, said lower member having its upper margin turned inwardly and downwardly and spaced therefrom, said upper portion having its lower margin turned outwardly and upwardly to embrace said downwardly turned margin of the lower member, and brackets fixed in a wall and extending outwardly beyond said interengaging marginal 95 portions of said members for supporting the flashing on the wall, the lower marginal portion of said lower member being turned inwardly below said brackets for retaining the members thereon.

In testimony whereof I have signed my name to this specification.

ALBERT G. NELSON.
